UNITED STATES PATENT OFFICE

2,545,561

HEATING ELEMENT FOR CONVECTION
HEATERS

Benjamin Spieth, Racine, Wis., assignor to
Modine Manufacturing Company, Racine, Wis.,
a corporation of Wisconsin

Application September 26, 1947, Serial No. 776,363

6 Claims. (Cl. 257—124)

1

This invention relates to heating elements for convection heaters where economy in the cost of manufacture and a minimum number of fabricated parts are of importance.

Due to the nature of the present heating element it is usually constructed of light gage and relatively expensive materials such as copper and brass, therefore, in order to provide strength and sufficient rigidity to resist external piping strains it is necessary to build as rigid a construction as possible, and though allowing for internal expansions at the same time maintaining production economies.

To this end I have devised a form of construction of the fins, the side plates and supporting means for the heating element for performing several functions and obtaining novel results.

One of the objects of this invention is to provide a fin-side plate combination which provides means whereby the side plates may be firmly attached to the fins.

Another object is to provide side plates which are also utilized as extended heating surfaces.

Another object is to solder or braze each and every fin to the side plates, whereby to prevent relative movement between the fins and the side plates due to expansion and contraction which movement otherwise results in scraping noises.

Another object is to provide side plates of light gage material provided with offset reinforcements, thus forming a relatively rigid piece.

Another object is to provide side plates that give stiffness to the fin-tube portion and prevent the light gage tubes from sagging.

Another object is to provide side plates attached directly to the end supports, thus allowing the fin-tube portion to float.

Another object is to provide a guard around the fin-tube assembly.

Another object is to provide fins with short flanges on their ends which are bonded to the side plates, thus providing a mechanically strong joint between the fins and the side plates.

Another object is to provide side plates bonded to the fins thereby gaining a greater area of secondary surfaces in contact with the air.

Another object is to provide supporting members at the ends of the structure which connect the side plates and at least one of said supporting members serving to give mechanical support to its associated header when the pipe is being screwed into the header.

Other objects and advantages will appear in the course of this specification and with all of said objects and advantages in view this inven-

2

tion consists in the several novel features herein-after fully set forth and more definitely pointed out in the appended claims.

The invention is clearly illustrated in the drawings accompanying this specification in which:

5 Fig. 1 is a plan partly broken away and partly broken out of a heating element for convection heaters embodying a simple form of the present invention;

10 Fig. 2 is a view partly in side elevation and partly in central vertical longitudinal section of the parts seen in Fig. 1, the line of section being indicated at 2—2 in Fig. 1;

15 Fig. 3 is a vertical cross section taken along the line 3—3 of Fig. 2 and showing the parts upon an enlarged scale;

Fig. 4 is an end elevation of the device looking in the direction of the arrow 4 in Fig. 1 and showing the device upon an enlarged scale;

20 Fig. 5 is a detail horizontal fragmental section taken on the line 5—5 of Fig. 3; and

Fig. 6 is a perspective view of one of the supporting members of the device.

Referring to said drawings, which are merely

25 illustrative of one embodiment of the invention, the reference characters 8, 8 designate the two side members of the heating element here shown in the form of elongated plates, to which are secured as by soldering or brazing a multiplicity

30 of heat radiating fins 9, the ends of each fin are formed with flanges 10 which are soldered or brazed to the side plates, and the latter are formed with outwardly offset reenforcing portions 11 between the parts of the side plates to which the

35 flanges 10 are soldered or brazed. The upper and lower edges of the side plates are formed with U-bends 11a to give added rigidity to the side plates. Slight spaces 12 are left between the ends of the fins and the offset reenforcing

40 portions 11 of the side plates. The fins are formed of very light gage metal and may be formed with stiffening beads 9a. The side plates may be formed of slightly heavier gage metal than the fins and by reason of the offset portions in

45 the side plates they are made very stiff and rigid. Soldered or brazed to the end portions of the side plates 8 are supporting members 13 which are formed with horizontal plate members 14

50 which have upwardly offset end portions 15 that terminate in downwardly extending wing members 16 which engage the side plates and are soldered or brazed thereto. The horizontal plate members 14 are formed at their outer ends with

55 downturned ribs or flanges 17 which may engage with suitable supports or brackets (not shown)

fastened to the walls of the cabinet in which the convection heater is installed.

Extending through holes in the fins are fluid conveying tubes 18, 19 which extend between and connect a supply header 20 to a return header 21. Both of the headers 20, 21 are non-circular in cross section, being here shown as of octagonal form and the header 21 may extend through an octagonal hole 22 formed in the horizontal part 14 of the supporting member 13.

Secured in openings in the inlet header and extending in opposite directions therefrom are two sub-headers 23 which may be of cartridge form and the tubes 19 at one end thereof open to the interiors of the sub-headers 23 and are soldered or brazed thereto. The corresponding end of the tube 18 enters the supply header 20 through an opening in its side wall. The other end of the tube 18 enters the return header 21 through an opening in one of its side walls and the corresponding ends of the tubes 19 are bent to form elbows 24, the ends of which enter the return header 21 through openings in its side walls and are soldered or bonded to said header. The lower end of the supply header 20 is internally threaded for the reception of a supply pipe 25 as is clearly seen in Fig. 2 and both ends of the return header 21 may be internally threaded to receive a return pipe 26 and a screw plug 27.

All of the parts of the heating element, at least at their contacting portions, are provided with a soldering or brazing material and the assembled heating element is placed in a suitable oven and heated to the fusing point of the solder or brazing material, which when set rigidly connect all of the contacting points and provide a rigid, sturdy and substantial heating element which can be economically fabricated.

Having thus described my invention, it is obvious that various immaterial modifications may be made in the same without departing from the spirit of my invention; hence, I do not wish to be understood as limiting myself to the exact form, construction, arrangement and combination of parts herein shown and described or used mentioned.

What I claim as new and desire to secure by Letters Patent is:

1. In a heating element for convection heaters, a pair of side plates each having outwardly offset longitudinally extending reenforcing portions, fins extending between said side plates and being formed with flanges bonded to the side plates, fluid conducting tubes extending through holes in said fins, a supply header connected to the tubes at one end thereof and a return header connected to the tubes at the other end thereof, and supporting members at the ends of the side plates each having a horizontal plate member, at least one formed with an opening corresponding to the cross section of the associated header and formed at its outer edge with a downturned retaining flange, said horizontal plate member terminating at its ends in two vertical downwardly projecting wing members bonded to the side plates.

2. In a heating element for convection heaters, a pair of side plates each having outwardly offset longitudinally extending reenforcing portions, fins extending between the side plates and being formed with short flanges bonded to the side plates, fluid conducting tubes extending through holes in said fins, a supply header connected to the tubes at one end thereof and a return header connected to the tubes at the other end thereof,

and supporting members at the ends of the side plates each having a horizontal plate member, at least one formed with an opening corresponding to the cross section of the associated header and formed at its outer edge with a downturned retaining flange, said horizontal plate member having upwardly offset end portions terminating at their ends in vertical downwardly projecting wing members bonded to the side plates.

10 3. In a heating element for convection heaters, a pair of side plates each having outwardly offset longitudinally extending reenforcing portions, fins extending between the side plates and being formed with short flanges bonded to the side plates, intermediate said offset portions, fluid conducting tubes extending through holes in said fins, a supply header connected to the tubes at one end thereof and a return header connected to the tubes at the other end thereof, and supporting members at the ends of the side plates each having a horizontal plate member having upwardly offset end portions terminating at their ends in vertical downwardly projecting wing members bonded to the side plates.

15 4. In a heat exchange structure, the combination of a fluid conducting tube, means associated with the respective ends of said tube for operatively connecting the latter to a fluid line, a plurality of fin elements, each having an opening

30 therein through which said tube extends, each fin element having a series of spaced, vertically and horizontally aligned flanges along a pair of oppositely disposed edges, with the flanges adjacent corresponding edges of the respective fin elements lying in a common plane extending parallel to a common plane containing the flanges along the other corresponding edges of the fin elements, and a pair of side plates, each positioned adjacent respective flanged edges of the fin elements,

35 45 said plates each being provided with outwardly offset, longitudinally extending portions, each of said portions being positioned between a pair of adjacent flanges of each fin element, said flanges being bonded to the respective portions of the plates intermediate said outwardly offset portions, the latter providing channels in which are positioned portions of the respective fin elements extending outwardly beyond the planes of said flanges.

50 5. In a heat exchange structure, the combination of a fluid conducting tube, means associated with the respective ends of said tube for operatively connecting the latter to a fluid line, a plurality of fin elements, each having an opening

55 therein through which said tube extends, each fin element having a series of spaced, vertically and horizontally aligned flanges along a pair of oppositely disposed edges, with the flanges adjacent corresponding edges of the respective fin elements lying in a common plane extending parallel to a common plane containing the flanges along the other corresponding edges of the fin elements, a pair of side plates, each positioned adjacent respective flanged edges of the fin elements, said plates each being provided with outwardly offset, longitudinally extending portions,

60 each of said portions being positioned between a pair of adjacent flanges of each fin element, said flanges being bonded to the respective portions of the plates intermediate said outwardly offset portions, the latter providing channels in which are positioned portions of the respective fin elements extending outwardly beyond the planes of said flanges, and a supporting member adjacent each pair of corresponding ends of said plates,

said supporting members each having a pair of spaced flanges extending therefrom in spaced, parallel relation secured to the respective plates.

6. In a heat exchange structure, the combination of a fluid conduit tube, a plurality of fin elements, each having an opening therein through which said tube extends, each fin element having a plurality of spaced, vertically and horizontally aligned flanges along a pair of oppositely disposed edges, with the flanges adjacent corresponding edges of the respective fin elements lying in a common plane extending parallel to a common plane containing the flanges along the other corresponding edges of the fin elements, and a pair of side members each positioned adjacent respectively flanged edges of the fin elements, the inner faces of said members having recesses therein, said recesses being positioned between adjacent flanges of each fin element, said flanges being bonded to the respec-

tive portions of the members adjacent said recesses, the latter providing spaces in which are positioned portions of the respective fin elements which may extend outwardly beyond the planes of said flanges.

BENJAMIN SPIETH.
